UNITED STATES PATENT OFFICE.

COLES A. CARPENTER, OF OYSTER BAY, NEW YORK.

APPARATUS FOR EXCAVATING AND SCREENING SAND, &c.

SPECIFICATION forming part of Letters Patent No. 288,545, dated November 13, 1883.

Application filed April 3, 1883. (No model.)

To all whom it may concern:

Be it known that I, COLES A. CARPENTER, of the township of Oyster Bay, in the county of Queens and State of New York, have invented a new and useful Apparatus for Excavating and Screening Sand, &c., of which the following is a specification.

My invention relates to an apparatus for excavating and screening sand and other materials; and it consists in the improved construction and combination of parts herein-after fully described and claimed.

In the accompanying drawings, forming part of this specification, Figure 1 represents a front view of an apparatus having my improvements embodied therein. Fig. 2 is a side view of the same. Fig. 3 is a rear view with a modified or additional arrangement of the receiving-bin and its parts, hereinafter again referred to. Fig. 4 is a plan view of the supporting-platform. Fig. 5 is a transverse section of the screening-cylinder provided with inner and outer sieves; and Fig. 6, the same, illustrating the manner of connecting the sieve-sections in position; Figs. 7 to 12, views show in detail various detached parts.

A' represents a platform mounted on rollers d, turning on stub-axles e, projecting from the sides of the platform. Four standards, A, are mounted on the platform A', and incline, as shown, to converge toward each other at their top, and enable bolts a' to secure them together at that point. Cross-beams D D are secured to the standards A, about midway thereof, and are supported at their rear projecting ends, d', by means of a vertical standard, D', located on the rear end of the platform A'. Each of the beams D D carries near the forward standards A a bearing, through which passes the shaft L, one end of which projects to receive a sprocket-wheel, K, the said shaft L also carrying pulleys k, around which pass the belts k', one of which is driven from the stationary engine b, located on the platform A', as clearly shown in Fig. 4, while the other belt communicates the motion it derives from its pulley to the supply-pump i of the engine.

The reference-letters a and c designate, respectively, the boiler and supply-tank erected on the platform and performing their offices

with respect to the engine proper, and the supply-pump i.

The sprocket-wheel K imparts its rotary movement by means of a drive-chain, K', to a second sprocket-wheel, K'', located on the end of and turning with a shaft, L', journaled in bearings secured to the front end of cross-beams k', attached to the standards A above and parallel with the cross-beams D. The said shaft L' has keyed thereon a pinion, K'', which meshes with and imparts motion to cog-wheels I² O², mounted, respectively, on the projecting ends of shafts I O, journaled in bearings in the cross-beams I³ O³, secured to the standards A respectively above and below the cross-beams k', and parallel therewith.

Centrally mounted on and revolving with the shaft I is a bevel-gear wheel, I', which meshes with and imparts motion to a gear-wheel, H, at right angles to the wheel I', and turning with a shaft, E, inclined, as shown in Figs. 2 and 3, the forward end of said shaft bearing on a cross-beam secured transversely of the front standards A A, in the rear of the gear-wheel H, (but omitted from the drawings to avoid complexity,) and the rear end passing through and bearing in a hanger, F, secured to a transverse bar, F', supported by the beams D D, the bearing-opening of said hanger F being vertically elongated to permit a limited vertical play of the rear end of the said shaft E therein.

On the extreme rear end of the shaft E is mounted a star or cam-head, G, Figs. 2 and 10, which rests on the upper side of the bar F'.

Rigidly mounted on the shaft E, between its bearings, are a series of spider-wheels, E', Figs. 5 and 6, the rims of which are perforated for the passage of the ends of a series of radial rods, E'', threaded their entire length to adapt them to be secured rigidly to the spiders by means of nuts and washers E'.

A screen, B, is formed of the cylindrical reticulated sections B', which are clamped by rods E' and blocks E'' by means of nuts E'.

A stationary screen, Q, Figs. 1, 7, and 8, composed of a series of parallel rods, q, bolted to curved cross-rods q', is secured to one of the standards A, and extends into the lower part of the forward end of the screening-cylinder B, so that the latter can revolve around it.

An inclined trough, V, is located between the inner side of the driving-belt and the cylinder-screen, and projects over the stationary screen Q at its rear end.

5. The shaft O carries a wheel, O', around which passes the chain M, carrying the excavating-buckets N, said wheel O' being composed of spider-wheels having studded peripheral ribs O⁴, over which the chain passes, 10 wood-sections O⁵, resting on collars O⁶, formed on the spokes of the spider-wheels, and forming a hexagonal support on which are tacked or nailed the edges of a series of canvas or other flexible strips or shields, O⁷, which extend transversely the width of the wheel O. 15
- A wheel, O⁸, similar to the wheel O, is mounted on and revolves with a shaft, O⁹, secured in suitable bearings at the base of the machine, and carries the belt M, which travels 20 around the same. The belt is composed of a series of links, M', (see Fig. 9,) having one end formed into a hook, m', adapted to engage the cross-bar m² of the link next preceding. At regular intervals along the belt the links are 25 provided with ears m³, which are perforated for the convenient attachment of the excavating-buckets. The recessed portions m⁴ of the links receive the studs on the wheels O' and O⁸, and facilitate traction.
30. A pulley, P, located between the forward projecting ends of the bars D, rests between the sides of the excavating-belt, and prevents the sagging of the same at the center thereof.
35. A platform or slide, W, arranged transversely beneath the screening-cylinder, is adapted to convey away the screened material, which the cylinder deposits upon it. The slide W communicates, at its lower end, 40 with a bin or receptacle, U, and in said bin or receptacle U is centrally pivoted, at r, an angle-platform, R, the outer end, r', of which is normally held horizontally by a weight or counterpoise, S, attached to the lever r² of said platform. Other slides and bins may be used where screens of different sizes are employed. The bin may be placed in the axial line or direction of the screen, as shown in Fig. 2, or at one side of the axial line, as seen in Fig. 45 50 55 3, the slide W being in either arrangement placed so as to direct the screenings to their destination, as shown. It is evident that both arrangements of bin may be used together, which may obviously be done, provided the slides are given the required direction, which would involve no invention.

A centrally-pivoted arm, r³, is connected by a rod, r⁴, at one end to the forward end, r, of the platform R, while a lever, r⁵, effects the 60 depression of the rod r⁴, and hence the downward movement of the platform R. When the platform R is in the position shown in Fig. 2, it closes the opening r⁶ of the bin U, but when in the position shown in Fig. 3, the 65 opening r⁶ is uncovered, and the material free to escape from the bin, the extended or outer

end of the platform R serving as a chute or guide for the material.

Supporting-wheels p' are journaled on axles p², bearing in extensions p³ of the forward 70 end of the platform A', while brackets E⁹, located on the outer sides of said extensions, are adapted for the longitudinal insertion and retention of hand-levers g, designed to be used by the attendants in shifting the position of 75 the apparatus.

From the foregoing description it will be apparent that the entire apparatus is adapted to be easily moved from place to place, that the hand-levers g can be readily removed from 80 their brackets to effect such movement, that the links composing the excavating-chain can be connected and disconnected with great facility, additional links being incorporated therein without affecting the balance of the 85 chain, and that the buckets can be firmly and rigidly connected to their respective links without the expenditure of much labor or time. Moreover, the peculiar construction of the chain-supporting wheels o' o⁸ insures 90 the positive movement of the excavating-chain and buckets thereover, but at the same time prevents the loose sand or other material from effecting an entrance to the working parts of 95 said wheels, and resulting in the clogging of the machinery. As the excavating-chain is rotated around the pulleys O' O⁸, the buckets on the forward portion of said belt which moves upward become filled with the material, and as they pass over the upper pulley, 100 O', to descend, they deposit their contents in the trough V, from whence it passes onto the stationary screen Q, which sieves it into the rotating cylinder B, which causes its separation and delivery onto the slide W. As the 105 revolutions of the pulleys O' O⁸ and excavating-belt M are effected from the intermediate connections with the engine on the platform, the gearing of the pinion H on the shaft of the screening-cylinder, with the gear-wheel on the shaft I, the revolution of the cylinder is produced, and its vertical agitation is secured by means of the cam-head G on the other end, the vertically-elongated opening in the bearing F permitting the vertical movement of 110 the shaft. The screened material passes from the slide W into the bin U, from whence it can be readily removed by means of the 115 tilting platform R and its connections.

Having now described my invention, what 120 I claim as new, and desire to secure by Letters Patent, is—

1. In an apparatus for excavating, screening, &c., the combination of a belt provided with excavating-buckets, belt-driving mechanism, an inclined cylindrical screen, means for giving rotary and vertical movement to said screen, and a stationary breaking-screen extending within the cylindrical screen, substantially as set forth.

2. In an apparatus for excavating, screening, &c., the bin U, having the opening r⁶, and

counterbalanced platform R, combined with a screen, and the slide W, for directing the screenings to the bin, substantially as set forth.

3. The combination, in an apparatus for excavating, screening, &c., of wheels over which the excavating - belt travels, provided with flexible coverings, substantially as and for the purpose set forth.

4. The combination, in an apparatus for excavating, screening, &c., of wheels over which

the excavating - belt travels, provided with studded peripheral ribs O⁴ and collars O⁶ on the spokes of said wheels, adapted to receive the sections O⁵, to which flexible sections are attached, substantially as set forth.

COLES A. CARPENTER.
